Primary Examiner — George J Ulsh*Assistant Examiner* — Jihyung Yoon(74) *Attorney, Agent, or Firm* — Lora J. Graentzdoerffer(57) **CLAIM**

The ornamental design for a shower control as shown and described.

DESCRIPTION

FIG. 1 is a perspective view of a shower control showing my design;

FIG. 2 is a front elevational view;

FIG. 3 is a rear elevational view;

FIG. 4 is a side elevational view;

FIG. 5 is another side elevation view;

FIG. 6 is a top plan view; and,

FIG. 7 is a bottom plan view.

The broken lines in the drawings show portions of a shower control which form no part of the claimed design.
